UNITED STATES PATENT OFFICE.

DANIEL J. MURNANE, OF SAN MATEO, CALIFORNIA.

HINGE.

Application filed February 16, 1925. Serial No. 9,399.

My invention relates to a frictional resistance element which is particularly adaptable for use in a hinge.

One object of my invention is the provision of a simple device for installation in a hinge or similar object to create the desired frictional resistance between the fixed and movable parts thereof.

Another object of the invention is to provide a frictional resistance element which will prevent to a large degree undesired movement of an open window.

Another object of my invention is the provision of a frictional resistance element which cannot be broken down by use, and which maintains a uniform value at all times, because of automatic adjustment to compensate for wear.

My invention possesses other objects and features of advantage, some of which with the foregoing, will be set forth in the following description of the preferred form of my invention which is illustrated in the drawings accompanied and forming part of the specification. It is to be understood that I do not limit myself to the showing made by said drawings and description as I may adopt variations of the preferred form within the scope of my invention as set forth in the claims.

Referring to the drawings:

Figure 1 is a plan view of a casement window hinge in which my frictional resistance element has been installed.

Figure 2 is a plan view of my device, a portion being broken away to show the construction.

Figure 3 is a cross sectional view, the plane of section being indicated by the line 3-3 of Figure 2.

In terms of broad inclusion my invention comprises a hinge embodying a friction element of particular usefulness in mounting the casement type of window. The hinge comprises a slideway adapted to be fixed on the window sill, and on which is mounted a slide to which is pivotally attached a plate adapted to be fixed to the lower or upper edges of the window sash. Motion is imparted to the slide when the window is moved, by means of a link which pivotally connects the sash and plate to the fixed slideway. Interposed between the slide and slideway are shoes resiliently engaging the slideway with a substantially constant pressure.

More in detail my hinge comprises a mounting for a casement window and consists in a plate 6 having suitable screw holes 7 to adapt it to be fixed to the sill. One edge of the plate 6 serves as a slideway 8 and is formed by curling the edge over in a cylindrical roll. Mounted in this slideway 8 to move back and forth therein, is a slide 9 having at each end on the inner edge, rolled portions forming arms 11 of such size as to fit easily within the inner portion of the cylindrical part of the slideway of the fixed plate 6. These arms are spaced apart and are adapted to hold between them the frictional element of my invention.

The friction element consists of two shoes 12 of generally semi-cylindrical form, the ends 13 of which converge so that a conical surface is provided at each end of each shoe. The two shoes are alike in shape and size and when placed together in the space between the arms 11 of the slide, provide a recess within them, in which a coiled spring 14 may lie. The parts are put together with an assembling jig which holds the spring under compression and when the jig is removed the expansion of the coiled spring presses the ends thereof into the conical ends 13 of the shoes, thus tending to separate the shoes and force them outwardly against the inner surface of the cylindrical portion 8 of the slideway. The spring is under compression between the conical ends of the shoes and is so designed that the desired frictional resistance is created by the shoes, with the result that a resistance of definite magnitude tends to prevent movement of the slide in the slideway. Wear on the spring is prevented by the shoes 12 which surround it and which tend to exert an even pressure over the entire spring, so that there are no particular points of contact which receive undue strain.

Pivoted to the slide 9 is a plate 16 provided with screw holes 17 for fixing it to the bottom or upper edges of the window sash, as the case may be, and pivotally connecting this plate to the slideway 6 is a link 18.

One of my hinges is mounted on the lower edge of the window and another on the upper edge, and when the window is moved to open or close it, the presence of the link 18 between the two parts enforces the sliding movement of the slide 9 in its slideway. The resistance element interposed between the

two plates is of such character that while the window may be readily moved because of the leverage offered, it nevertheless tends to remain in the position in which it is placed.

My hinge permits the window to be opened so that access may be had to both sides of the glass, and the window will stay where it is put against any tendency of the wind 10 to move it.

While I have shown my invention embodied in a hinge it will be obvious without special illustration that my resistance element may be incorporated between any two 15 elements or members between which it is desired to create a resiliently exerted frictional resistance.

I claim:

1. A casement window mounting comprising a fixed split-cylindrical slideway, a slide arranged on said slideway, a plate pivoted to the slide, a link fixedly pivoted at one end to said slideway and at the other end to said plate, and cylindrical shoes for 25 creating a frictional resistance between the slide and the slideway.

2. A casement window mounting comprising a fixed slideway, a slide arranged on said slideway, a plate pivoted to the slide, a link 30 pivotally connecting said plate to said slideway, a pair of shoes mounted in said slide and having alined conical ends, and resilient means pressing into the conical ends for forcing the shoes into engagement with said slideway.

3. A casement window mounting comprising a fixed slideway, a slide arranged on said slideway, a plate pivoted to the slide, a link 40 pivotally connecting said plate to said slideway, a pair of shoes mounted in said slide, and a coiled spring between said shoes for pressing the shoes into engagement with said slideway.

4. A hinge for a casement window comprising a fixed slideway, a slide mounted 45 on said slideway and provided with a recess, a pair of hollow shoes in said recess and bearing on said slideway, a coiled spring interposed between the shoes for pressing them

against the slideway, a plate pivotally mounted on said slide, and a link pivotally connecting the plate and slideway.

5. In combination with a slideway and a slide arranged therein, a pair of shoes 55 mounted in the slide and each having a recess with conical ends, and a coil spring under compression arranged in the recesses and bearing in the ends thereof.

6. In combination with a fixed slideway and a slide arranged therein, a pair of hollow shoes mounted in the slide and having alined conical ends, and a coiled spring compressed between the ends and within said shoes for creating a frictional resistance between the fixed and the movable parts of the 65 hinge.

7. A frictional resistance element comprising a slideway, a slide, a pair of hollow shoes, each of said shoes having alined conical ends, and resilient means bearing against 70 said ends for pressing the shoes apart.

8. A frictional resistance element comprising a slideway, a slide, a pair of hollow shoes having alined conical ends, and a spring interposed between the shoes and 75 resiliently engaging against the conical ends to press the shoes apart.

9. A casement window mounting comprising a fixed slideway, a slide arranged on said slideway and having arms disposed 80 at each end on the inner edge thereof, a plate pivoted to the slide, a link pivotally connecting said plate to said slideway, and means interposed between said arms for creating a frictional resistance between the 85 slide and the slideway.

10. A casement window mounting comprising a fixed slideway, a slide arranged on said slideway, a plate pivoted to the slide, a link pivotally connecting said plate to said slideway, and a coiled spring mechanically interposed between the slide and 90 the slideway for creating a frictional resistance therebetween.

In testimony whereof, I have hereunto set 95 my hand.

DANIEL J. MURNANE.
